UNITED STATES PATENT OFFICE.

WARREN H. TAYLOR, OF STAMFORD, CONNECTICUT.

IMPROVEMENT IN WASHING-MACHINES.

Specification forming part of Letters Patent No. 148,004, dated February 24, 1874; application filed June 13, 1873.

To all whom it may concern:

Be it known that I, WARREN H. TAYLOR, of Stamford, in the county of Fairfield and State of Connecticut, have invented certain Improvements in Washing-Machines, of which the following is a specification:

This invention relates to a washing-machine that is constructed in a simple and durable manner, and adapted to be applied to any size tub; and the invention consists of a large corrugated wood roller with a metal facing, three small smooth or plain, rollers, one of which is smaller than the rest, arranged underneath the large roller, a clamping device, and set-screw for attaching the machine to the tub and adjusting it thereon, the said parts being mounted on a suitable frame-work, as hereinafter described.

In the accompanying drawings, in which similar letters of reference indicate like parts in the several figures, Figure 1 is a side view of my device attached to an ordinary tub, with a portion of the tub broken away. Fig. 2 is a top view of the washer. Fig. 3 is a vertical cross-section through the center of the rollers. Fig. 4 is the adjusting-screw. Fig. 5 is a view of the spring-bearing of the corrugated roller detached.

In a suitable frame-work, consisting of a base, *a*, and vertical side pieces *b b*, a wooden corrugated roller, *A*, is mounted.

As is well known, these rollers, when made of wood, as usual, rapidly become cracked, roughened, and worn by the action of the water and garments in washing; and in order to obviate this, this roller is covered or faced with sheet metal, as indicated at *H*, Fig. 3, whereby it is greatly strengthened and made much more durable.

Underneath roller *A*, and journaled in the side pieces *b b*, are three, more or less, small rollers, *F F' F*, the central roller, *F'*, being smaller than the others, to correspond with the arc of revolution of roller *A*. These rollers are of wood or other material, and are made with a smooth, plain surface. The roller *A* is supported in spring-bearings within the

sides *b b*, which are composed of a pin, *D*, around which a spring, *G*, is coiled, (see Fig. 5, and dotted lines, Fig. 1,) whereby the roller *A* is permitted to yield to the pressure of the garments as they pass between the said roller and the smaller ones. One end of the shaft of roller *A* is extended a short distance beyond the frame-work, and to it a crank-handle, *c*, is attached, for rotating said roller. To one of the sides *b* two standards, *B B*, are attached, at such an angle as to resemble a *V*, and they are also inclined slightly outward from the frame, and to these standard-arms *B' B'* are secured by means of hinges *d*, of such length as to leave a space of about an inch between the two parts. Bolts *e e* extend from standards *B* through the arms, and have their ends threaded, on which thumb-nuts *ff* are screwed, these being on the outside of the arms. An adjusting-screw, *c*, is set in the lower part of the frame-work. The standards *B*, arms *B'*, screw-bolt, and adjusting-screw, I term the clamping device, for, by means thereof, the machine is secured to the edge of a tub, as indicated by *E*, the arms and screw-bolt serving to clamp the frame to the tub, and the screw *c* admitting of its adjustment to the proper position on any size tub.

Having thus described my invention, what I claim as new, and desire to secure by Letters Patent, is—

1. In a washing-machine, the clamping device constructed with standards *B* and arms *B'*, hinged thereto, and adjustable by means of screw-bolts, in combination with an adjusting-screw, substantially as shown and described.
2. In a washing-machine, the combination of a metal-faced corrugated roller journaled in spring-bearings, (three, more or less,) plain rollers, and the clamping device, all constructed substantially as herein shown and described.

WARREN H. TAYLOR.
